UNITED STATES PATENT OFFICE.

FRANCIS E. BUXTON, OF DAYTON, OHIO.

ADJUSTABLE JOURNAL-BOX.

1,109,642.

Specification of Letters Patent.

Patented Sept. 1, 1914.

Application filed January 16, 1909. Serial No. 472,762.

To all whom it may concern:

Be it known that I, FRANCIS E. BUXTON, a citizen of the United States, residing at Dayton, in the county of Montgomery and State of Ohio, have invented certain new and useful Improvements in Adjustable Journal-Boxes in addition to that secured to me by Letters Patent of the United States August 11, 1908, No. 895,425, and referred to 5 by the same title as above.

The following is a full and accurate specification of my invention, being such as will enable others to make and use the same.

My invention relates to improvements in 15 journal-boxes in which there is a unitary arrangement of the bearing; there being engaged supporting collars disposed about the extreme ends of the bearing sleeve and rotatable therewith, and an intermediate sleeve 20 positioned around the said bearing sleeve, having its inner central portion engaging a threaded portion of the bearing sleeve, and independently rotatable therewith within a fixed casing.

25 The objects of my invention are: first, to provide a wear-compensating box for small journals; second to provide a box constructed in a manner to dispense with oil wastes that are so destructive to manufacturing 30 plants. I attain these objects by the mechanism illustrated in the accompanying drawings in which—

Figures 1 and 2 illustrate the complete box, being an elevation of the front end, and 35 a side elevation of the box partly in section; the lower parts broken away showing the general arrangement. Fig. 3 is a section through the case and sleeve, in part taken on line $x-x$ referring to Fig. 40 4, having the upper part of the sleeve broken away. Fig. 4 is a front end elevation of the box, the front supporting collar and journal being removed to show the bearing sleeve mechanism. Fig. 5 is an end elevation 45 of front supporting collar, the parts being in section to illustrate the inclosed sectional oil ring mechanism. Fig. 6 is an enlarged perspective view of the eccentric oil ring and wedge adjustment, for retaining 50 the oil. Fig. 7 is an inner end elevation of the front supporting spanner collar, illustrating the spacing lug supports. Fig. 8 is a longitudinal section through the outer case 55 and the engaging collars, the bearing sleeve proper being removed. Fig. 9 is a side elevation of the bearing sleeve unit, showing its

position and a sectional view of the surrounding compression sleeve. Fig. 10 is an end elevation of the rear supporting collar, illustrating the triangular supporting lugs. 60 Fig. 11, is a sectional view of the box complete taken on the line $y-y$ referring to Fig. 3, showing the practically quartered effect of the bearing sleeve part. Figs. 12 and 13, are enlarged views, being side and 65 end elevations of the front supporting collar and outer case, having parts broken away to illustrate the screw lock and the oil ring adjustment of the same. Fig. 14, is an enlarged view of the front spanner supporting 70 collar as it appears looking at the top, having the side parts broken away and shown in section, illustrating the oil ring segments, the wedge and the screw adjustment. Fig. 15 is a side elevation of the box, inclosed in 75 a reversible outer casing slightly modified in form. Figs. 16 and 17 are views showing the front and rear elevation, respectively, of the construction shown in Fig. 15, to illustrate the spanner collar and the blank rear 80 cap. Fig. 18 is a vertical plan of the box complete. And Fig. 19 is a view showing the preferred form of the front supporting spanner collar with the spanner wrench applied. 85

Similar letters refer to similar figures throughout the several views.

In the accompanying drawings A represents an outer cylindrical casing; midway between its ends and positioned vertically 90 over said casing is an opening having threads formed therein to receive a locking screw, a^5 , that will be explained presently; at the base of the casing are placed ribs, a^4 , that rigidly secure the casing to the main 95 frame. Near the front end of the casing A is provided a number of adjusting taper studs $a-a'$, the office of which will be mentioned presently, and formed central and parallel through the fixed casing is an aperture much larger than the journal to be carried. 100

B is a cylindrical sleeve, there being formed on its periphery and midway between its ends a number of equidistant slots 105 B' to receive the locking screw a^5 to prevent its rotation, forward and backward within the outer casing A.

Formed centrally within the sleeve B, is provided a round opening as indicated having longitudinally convergent walls on which are formed equidistant from the ends 110

- a threaded portion to engage the inner bearing sleeve element presently referred to. In the annular conical space between the said sleeve opening and the journal G, is placed 5 a unitary arrangement of bearing sleeve supports C, formed separate on their exterior conical portions within the sleeve B, but being joined compressibly and expansively together by a suitable bearing lining at f, substantially as shown in the drawings.

The bearing sleeve element C, is stationary relative to its longitudinal action and practically extends through the full length of the casing, said bearing sleeve C is reduced at its back end to engage substantially 15 within the sleeve B, and of a proper form to allow it to extend a proper distance beyond the front end of the sleeve B, which will be referred to later.

- 20 On the periphery of the bearing sleeve C, in the attached drawings, is formed flaring longitudinal grooves c^5 their side margins converging practically together and extending the full length of the bearing sleeve 25 C. Said grooves are ninety degrees apart, and formed on lines running parallel with the axis of the journal G. Clearance slots f' are formed at the base of the said grooves, that extend inward to the surface 30 of the journal G, they being the means provided for lubrication.

On the periphery of the bearing sleeve and a proper distance between its ends are formed threads c^4 that engage with corresponding threads b , within the sleeve B. The extreme ends of the bearing sleeve C, are supported by flanged collars E and D, formed to fit within the casing A in their relative positions and free to rotate therein.

- 40 A groove 2 is provided on the reduced diameters of the collars E and D and at the base of the same is provided a plurality of perforations e^8 that receive the locking studs $a-a'$, referring to Figs. 5 and 12, substantially locking the collar E after the bearing sleeve C has been adjusted. On the inner surface of the supporting collars E and D, are provided triangular lugs e^4 and D^4 extending inward and of a proper form to 45 register and interlock with the bearing sleeve C, being the means for the said bearing sleeve to be rotated by the collar E, by applying the spanner K.

Provided in the shaft openings of the collars E and D, are eccentric grooves to receive sectional oil rings E, e , and e' of like form and preferably made of fiber, the central opening of the oil ring $e-e'$ being concentric with the journal G; the larger ends of the oil ring segments $e-e'$ are alike and are provided with alining grooves e^5 registering as indicated with the tongues E^2 of like form provided on wedge E' . The reduced ends e^6-e^7 of the segments $e-e'$ are formed to overlap 65 slightly at an angle to facilitate their appli-

cation and adjustment. It should be evident that the said fiber segments $e-e'$ after a period of service will become slightly worn by reason of their close engagement with the journal G. Then sufficient fiber 70 may be removed at e^6-e^7 and adjusted again by the screw e^2 , preventing the escape of the oil. The segmental oil ring $e-e'$ in the collar D, is substantially the same in action, and the adjustment is provided through the 75 opening in the casing A at a^7 .

By the above description and the accompanying drawings it should be evident that I have provided means whereby the journal and the relative parts of the box are completely lubricated, the box working equally 80 as well when placed in a vertical position.

In the foregoing description I wish to make plain that the preferably gray iron bearing sleeve C, is not designed to be dependable as a unit in action, but it is formed into a plurality of lobes spaced apart and held conjunctively together by its lining at f there being slots and intermediate perforations formed at the base of the flaring 90 grooves, employed for the reason before stated. More specifically stated, the said bearing sleeve C, after being assembled within the casing A, is supported at its extreme ends by the collars E and D, interlocking within the groove c^5 and supported intermediately by the sleeve B. It is obvious that when releasing the locking screws $a-a'$ and turning the spanner collar E, the bearing sleeve C and the collar D will be 100 caused to rotate, equally compressing the bearing sleeve C radially toward the journal G, by reason of its angular threaded portion engaging within the sleeve B, while a reverse motion of the collar E will cause the 105 sleeve B to travel longitudinally backward, allowing the bearing sleeve C, to extend normally. It is also evident that, by releasing the screw lock a^5 and turning the collar E with spanner wrench K as before, 110 rotation of the complete inner box as a unit is provided thereby bringing the less worn surface of the bearing sleeve into action independent of its radial adjustment.

In practice to assemble my improved box, 115 I proceed in the following manner: The outer casing being in position I first place the collar D, at the back end of the casing; I then place the sleeve B, in its position within the casing A, and screw down the 120 lock a^5 to fit into the slot B' . The sleeve B being held securely, I then enter the reduced end of the bearing sleeve C, within the conical aperture of sleeve B. I now turn the said bearing sleeve C, until it registers at a 125 point previously indicated, being now in threaded contact within the sleeve B. I now place the collar E in its position interlocking it with the bearing sleeve as indicated. I now adjust the screws $a-a'$, and the com- 130

plete box is now ready to receive the journal G, to be carried. I now adjust the oil rings $e-e'$ by the screws e^2 in front and rear. In order to adjust the bearing radially, I have only to turn the front collar E, with the spanner and lock by the screws $a-a'$. When expedient to rotate the bearing to equalize the wearing surface, I release the screw a^5 and turn the end collar E, with the spanner 10 and lock by adjusting the screw a^5 .

In Figs. 15, 16, 17, and 18, I have shown a slightly modified form; the casing H is provided with a removable cap H'; the bearing sleeve proper can be reversed end to end, for reasons not necessary to mention. Collar J is designed for the spanner adjustment to economize space; the end cap J' being blank requires no oil ring; in other respects the modified form is substantially the same as the preferred construction.

Having shown and described the construction, and given the best means known to me for the operation of my journal-box, I desire it to be understood that various interchanges 25 may be made in the manner of assembling, in accordance with the varied requirements of service to be performed, without departing from or sacrificing any of the advantages thereof.

What I claim and desire to secure by Letters Patent is:—

1. A journal box comprising in combination with a fixed outer casing and a journal to be supported, a rotatory sleeve located in 35 the casing, means for moving said sleeve longitudinally forward and backward independent of its rotation within the casing, a compressible sleeve movably attached to and supported within the first named sleeve, 40 a pair of collars interlocking with said bearing sleeve and movable therewith, and means for locking the bearing sleeve, the casing, the movable sleeve, and the collars into a unit after they have been adjusted 45 as desired, all substantially as shown and described.

2. An adjustable journal box comprising in combination with a casing and a journal projecting therethrough, a bearing sleeve disposed through the casing, said bearing sleeve being formed with a plurality of outwardly flaring grooves formed in its periphery and extending throughout its length on lines parallel to its axis, a second sleeve of less length than the bearing sleeve and adapted to be moved longitudinally within the casing and surrounding the said bearing sleeve and having threaded connection therewith, a plurality of collars 55 adapted to register with said grooves of the bearing sleeve, means for the adjustment of the bearing sleeve relative to the journal without disturbing the radial adjustment of the bearing sleeve, and means 60 for locking the parts together after adjust- 65

ment has been made, all substantially as shown and described.

3. The combination with a fixed casing and a journal projecting therethrough, a bearing element disposed about the journal, 70 a screw sleeve slidably engaging with the casing, there being a plurality of equidistant slots formed in the periphery of the said sleeve and extending longitudinally thereof and affording means for locking the sleeve, there being a conical aperture formed within the sleeve a portion of which is threaded to engage with the bearing element in order to afford means for the longitudinal movements of the sleeve with relation to the casing, a plurality of collars interlocking within the opposite end portions of the bearing and operative therewith to provide means for the radial adjustment of the bearing element.

4. A journal box or the like comprising a fixed casing, a plurality of adjusting taper screws carried thereby, a plurality of supporting collars disposed at the ends of the casing and movably connected thereto, an inner or bearing sleeve having right angular grooves formed on its exterior to interlock with corresponding projections carried on the supporting collars, a plurality of bearing sleeve projections having their exterior faces formed circular, an outer sleeve disposed around the bearing sleeve and having interior threads meshing with threads formed around sections of the central portion of the bearing sleeve, means for rotating the bearing sleeve and the outer sleeve together for circumferential adjustment, and means carried by the casing for locking the connected sleeves therewith, all substantially as shown and described.

5. In a journal boxing, the combination with a fixed casing and a rotary shaft, a movable sleeve located within the casing, means for locking said sleeve at various positions circumferentially and longitudinally, 100 a bearing sleeve provided with a reduced conical exterior engaging a reverse conical aperture in the first mentioned sleeve and having threaded portions meshing with said bearing sleeve and adapted to positively control the movements of the sleeves, a plurality of collars adapted to actuate the bearing sleeve, an eccentric oil ring positioned in the casing, and a wedge to retain the oil ring in engagement with the shaft, all substantially as described.

6. A journal-box having in combination with a fixed casing and a journal projecting therethrough, a movable sleeve and a bearing sleeve, a plurality of supporting 115 collars each having a plurality of inwardly projecting lugs, a sectional oil ring carried within each of said collars and disposed around the journal, a plurality of companion segments, a wedge formed with in 120

wardly projecting side angles registering with said companion segments to provide means for their radial adjustment with relation to the journal, all substantially as described.

7. In a journal-box, the combination with a fixed casing having a comparatively large aperture therethrough and a comparatively small journal disposed through said aperture in the casing, a unitary mechanism disposed about the journal and detachably connected to and located centrally of said casing and comprising a rotary bearing sleeve which is conical as to its exterior and having a plurality of radial grooves disposed therethrough, a plurality of collars each having a plurality of inwardly disposed projections formed integral therewith, an intermediate sleeve disposed around said bearing sleeve and having threaded engagement therewith at their central portions to provide means whereby the bearing may be adjusted by its rotation, a plurality of oil-rings located in said collars, and means for the adjustment 25 of said oil-rings, all substantially as described.

8. A journal-box comprising in combination with a fixed casing and a rotary shaft, a pair of movable collars located at the ends 30 of the casing, there being annular recesses within said collars, an intermediate rotary bearing-sleeve having its exterior formed cone-like and its larger end portion reduced in order to fit in said collar recesses, a plurality of lugs located on the inner faces of 35 said collars and adapted to interlock with grooves formed in said bearing sleeve, oil-rings carried within the collars, and means for retaining the oil-rings in position, all 40 substantially as shown and described.

9. In combination with a fixed casing and a journal projecting therethrough, an inner sleeve disposed around the journal, an outer sleeve disposed around between the inner 45 sleeve and the casing, there being an aperture formed through the casing for said sleeves, means for frictionally engaging said sleeves, threads connecting the sleeves, a pair of rotary collars, and means for adjusting said collars circumferentially, all 50 substantially as shown and described.

10. In a journal boxing, the combination with a fixed casing and a rotary shaft disposed therethrough, a sleeve B located within 55 the casing and spaced from the shaft, means for locking said sleeves at any required position circumferentially and longitudinally, a bearing sleeve C provided with a conical exterior fitting the reverse conical 60 interior of sleeve B, a threaded connection

between said sleeves adapted to control the endwise movements of sleeve B, the said bearing sleeve C being composed of a tubular lining having slots therethrough fitting around said shaft and a plurality of separated lobes fixed on the periphery of said lining and adapted to fill the space between the lining and the sleeve B, all substantially as described.

11. A journal-box comprising a casing 70 having a rotary shaft extending therethrough, an outer sleeve located in the casing and spaced from the shaft, means for locking said sleeve to the casing, an inner sleeve having a conical exterior fitting the 75 reverse conical interior of the outer sleeve, a threaded connection in the central portion of said sleeves to control the endwise movements of the outer sleeve, said inner sleeve being composed of a tubular lining adapted 80 to fit around said shaft, said tubular lining being partially divided by sets of longitudinal sectional clearance slots into sections, a plurality of lobes secured on the periphery of said tubular lining, there being one of 85 said lobes located between each two sets of said slots, collars for supporting the inner sleeve, and eccentric oil-rings located in said collars, all substantially as shown and described.

12. In a journal-box including an inclosing casing having a rotary shaft extending therethrough, a sleeve B located within the casing and spaced from the shaft and having a conical central aperture therethrough which is concentric with the shaft, a bearing sleeve C having a conical exterior adapted to fit the interior of sleeve B, the sleeve C being composed of a tubular lining having slots therethrough which extend longitudinally thereof and a plurality of spaced-apart lobes secured around on the periphery of said lining, threaded connection between the periphery of said lobes and the interior wall of sleeve B, collars E and D for supporting the ends of sleeve C, there being eccentric grooves formed in the collars E and D, fibrous sectional eccentric oil-rings located in said eccentric grooves, and means for adjusting said oil-rings to prevent the 105 escape of oil, all substantially as shown and described.

In testimony whereof I have hereto subscribed my name in the presence of two witnesses.

FRANCIS E. BUXTON.
